PHOSPHATIC FERTILIZER

Friedrich P. Kerschbaum, Winter Haven, Fla.,
assignor to Harold T. Stowell, Washington,
D. C.

No Drawing. Application September 30, 1936,
Serial No. 103,458. In Austria October 7,
1935

5 Claims. (Cl. 71—46)

The invention relates to the production of phosphatic fertilizers and particularly to the production of fertilizers by the conversion of the phosphoric acid content of mineral phosphates into available form. 5

A principal purpose of the invention is the production of phosphatic fertilizers from mineral phosphates.

A further purpose of the invention is to provide a process whereby the phosphoric oxide content of mineral phosphates may be made available for fertilizer purposes without the use of acid treating agents.

It has been found that by a suitable choice of proportions and conditions it is possible to bring about a reaction between tri-alkali metal ortho-phosphates and mineral phosphates, apatites, such as Florida pebble phosphates, Morocco phosphates or flotation concentrates, whereby substantially the entire phosphorous content of the materials is converted into ammonium citrate-soluble form.

Instead of a tri-alkali metal phosphate, such as Na_3PO_4 or K_3PO_4 , substances capable of forming such phosphates under the conditions of the process may be used, for example, mixtures of alkali metal meta- or pyro-phosphates, or mono- or di-alkali metal ortho-phosphates, with the corresponding proportion of alkali metal hydroxide or carbonate to give the tri-alkali metal ortho-phosphate. Such substances are therefore substantial equivalents of tri-alkali metal phosphate in the method of the invention.

It has been found that to obtain a satisfactory conversion of the phosphatic material to a product of high content of ammonium citrate soluble phosphorus, it is necessary to treat the mineral phosphate with the tri-alkali ortho-phosphate, or its equivalent, in the amount of at least 0.5 mole, and preferably about 0.8 mole, of P_2O_5 as tri-alkali ortho-phosphate to every mole of P_2O_5 in the mineral phosphate and it is preferable to carry out the treatment at a temperature not substantially exceeding about 1200° C.

It has further been found that the conversion of the mineral phosphate into available form is greatly promoted by the presence of alkali metal chlorides, such as sodium and potassium chlorides or any alkali metal salt of an anion that does not chemically react with the mineral phosphate, such as alkali metal nitrate. In the presence of these promoting agents a substantially quantitative conversion of the mineral phosphate into ammonium citrate-soluble form may be effected at temperatures as low as 800° C., or even lower,

while in the absence of such promoters a temperature of about 1000° to 1100° C. is preferable. The promoting agent is advantageously used in an amount of at least one mole, preferably two to three moles or more, per mole of tri-alkali metal phosphate or its equivalent. 5

The following examples are illustrative embodiments of the principles of the invention:

1. Fifty kilograms of calcined Florida pebble phosphate containing 36.55% P_2O_5 was mixed 10 with thirty-eight kilograms of technical trisodium phosphate containing 38.26% P_2O_5 . The mixture was heated to a temperature of about 1000° C. for about 1½ hours. The product contained 38.55% P_2O_5 of which 99.0% was ammonium citrate soluble and 99.4% citric acid soluble. The pH of the product was 10.5.

2. The trisodium phosphate of Example 1 was replaced by an equivalent amount of an equimolecular mixture of sodium metaphosphate and 20 sodium carbonate. In this case also 99% of the P_2O_5 content of the product was ammonium citrate soluble.

3. Fifty kilograms of the calcined Florida pebble phosphate used in Example 1 was mixed with 25 thirty-eight kilograms of technical trisodium phosphate and fifty kilograms of potassium chloride. The mixture was heated to a temperature of 800 to 850° C. for about 1½ hours. The product contained 23.5% K_2O and 24.5% P_2O_5 , of 30 which 11.1% was water-soluble, 94.7% was ammonium citrate soluble, and 95.6% citric acid soluble. The pH of the product was 11.3.

The conversion process may be advantageously effected in a rotary kiln, although other apparatus, for example, a shaft furnace may also be used. It is sometimes advantageous, for example, when operating in a shaft furnace, to form the mixture of materials into agglomerates before charging into the furnace. A particularly advantageous method of operating the process is to bring about the reaction on a traveling pallet machine, of the type of the well-known Dwight-Lloyd sintering machine, in which case all or a part of the fuel necessary to provide the necessary temperature may, if desired, be added to the charge on the machine. 35 40 45

The phosphatic raw material may be advantageously pretreated or enriched by treating it, for example, with the residual gases from a 50 phosphorus blast furnace or other gases containing residual amounts of phosphorus, phosphorus pentoxide or phosphoric acid, or even with the weak phosphoric acid containing water from a phosphorus condensing operation. In this way 55

it is frequently possible to increase the P_2O_5 content of phosphatic raw materials by as much as 20%. The amount of tri-alkali metal phosphate used for the conversion of such enriched phosphatic materials may be reduced with advantage to as low as 0.5 mole (equivalent P_2O_5) to each mole of P_2O_5 in the treated phosphatic material.

It will be apparent from the foregoing description that the invention provides a simple and economical method for the conversion of phosphatic materials into highly valuable basic fertilizers and particularly mixed fertilizers which may contain, in addition to P_2O_5 , K_2O , Na_2O , CaO , and other desirable components.

It will further be apparent that the invention is not limited to the illustrative examples and that the conditions of operation, for example, the temperature under which the most effective conversion of the most economical results are obtained, will vary with the other conditions, such as the relative proportions of the materials, the character of the phosphatic raw material, the time of heating and the like.

I claim:

1. Process for the production of phosphatic materials suitable for fertilizers, comprising heating a mixture of a mineral phosphate and a tri-alkali metal orthophosphate, in the proportion of at least 0.8 mole of P_2O_5 in the alkali metal phosphate to each mole of P_2O_5 in the mineral phosphate, to a temperature of from about 1000° to about 1200° C.

2. Process for the production of phosphatic materials suitable for fertilizers, comprising heating a mixture of a mineral phosphate and a tri-alkali metal orthophosphate, in the proportion of at least 0.8 mole of P_2O_5 in the alkali metal phosphate to each mole of P_2O_5 in the mineral phosphate, to a temperature of from about 800° to about 1200° C., in the presence of at least one mole of a conversion-promoting agent of the group consisting of the alkali metal chlorides to

each mole of trialkali metal phosphate or its equivalent.

3. Process for the production of phosphatic materials suitable for fertilizers, comprising heating a mixture of a mineral phosphate and a tri-alkali metal orthophosphate, in the proportion of at least 0.8 mole of P_2O_5 in the alkali metal phosphate to each mole of P_2O_5 in the mineral phosphate, to a temperature of from about 800° to about 1000° C., in the presence of at least one mole of a conversion-promoting agent of the group consisting of the alkali metal chlorides to each mole of trialkali metal phosphate or its equivalent.

4. A process for the production of phosphate materials suitable for fertilizers, comprising heating a mixture of a mineral phosphate, which has been treated with a substance of the group consisting of phosphorus pentoxide and phosphoric acid to increase the P_2O_5 content of the phosphate, and a trialkali metal phosphate, in the proportion of at least 0.8 mole of P_2O_5 in the alkali metal phosphate to each mole of P_2O_5 in the original mineral phosphate, to a temperature of from about 1000° C. to about 1200° C.

5. A process for the production of phosphate materials suitable for fertilizers, comprising heating a mixture of a mineral phosphate, which has been treated with a substance of the group consisting of phosphorus pentoxide and phosphoric acid to increase the P_2O_5 content of the phosphate, and a trialkali metal phosphate, in the proportion of at least 0.8 mole of P_2O_5 in the alkali metal phosphate to each mole of P_2O_5 in the original mineral phosphate, to a temperature of from about 800° C. to about 1200° C. in the presence of at least one mole of a conversion-promoting agent of the group consisting of alkali metal chlorides to each mole of trialkali phosphate or its equivalent.

FRIEDRICH P. KERSCHBAUM.
